[57] **CLAIM**

The ornamental design for a combined container and closure cap, as shown and described.

DESCRIPTION

FIG. 1 is a perspective view of a combined container and closure cap showing our new design;

FIG. 2 is a top plan view thereof;

FIG. 3 is an enlarged exploded fragmentary perspective view thereof, shown for ease of illustration;

FIG. 4 is a front elevational view of FIG. 1, the undisclosed opposite side being identical;

FIG. 5 is a side elevational view of FIG. 1, the undisclosed opposite side being identical; and,

FIG. 6 is a bottom plan view of FIG. 1.

FIG. 4.

FIG. 5.

FIG. 6.
